ATTORNEY

UNITED STATES PATENT OFFICE.

FRED MARTINSON, OF HYDRO, MONTANA.

COLLAPSIBLE CHURN-FRAME.

1,250,923.

Specification of Letters Patent. Patented Dec. 18, 1917.

Application filed April 13, 1917. Serial No. 161,837.

To all whom it may concern:

Be it known that I, FRED MARTINSON, a citizen of the Dominion of Canada, residing at Hydro, in the county of Blaine and State of Montana, have invented certain new and useful Improvements in Collapsible Churn-Frames, of which the following is a specification.

This invention relates to supporting frames, and more particularly to collapsible frames for supporting churns and similar vessels.

The object of the invention is to provide a simply constructed and strong frame of this character which may be quickly and easily set up and collapsed without the use of tools.

Another object is to provide a frame of this character, the braces of which when in open operative position securely and reliably hold the frame in upright position against collapse and can only be folded after the locking bar constituting a part of the frame is released.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents an end view of a frame constructed in accordance with this invention with the churn in the form of a barrel shown suspended therein in dotted lines, and frame shown collapsed in dotted lines,

Fig. 2 is a side elevation thereof shown in open position in full lines and in partially collapsed position in dotted lines, the churn being shown supported in said frame in dots and dashes, and

Fig. 3 represents a detail perspective view of one of the bearings which supports the churn with the parts thereof arranged in juxtaposition ready for assembling.

In the embodiment illustrated, the frame constituting this invention is preferably constructed of angle iron and comprises two A-shaped end members 1 and 2, the cross bar 3 of which is composed of two sections 4 and

5 pivotally connected as shown at 6 and with their outer ends pivotally connected to the side bars 8 and 9 of the frames 1 and 2. The pivotally connected ends of these sections 4 and 5 are arranged in lapping relation with the horizontally disposed flange of one section cut away at its pivoted end as shown at 7, the edge of said cut away portion being overlapped by the flange 7' on the other section so that when these sections are arranged in longitudinal alinement as shown in Fig. 1, the overlapping flange 7' will operate to hold the sections rigidly against further downward movement and yet permit the sections to open upwardly into folded position when the frame is to be collapsed.

The side bars 8 and 9 of these A-shaped frames are provided at their lower ends with laterally extending surface engaging plates 10 and at their upper ends which are pivotally connected with pintle receiving bearings 11 which are made in the form of sections 12 and 13 one carried by one side bar and the other by the other side bar and each having complementary hinge knuckles 14 and 15 through which the pintle 16 is passed for hingedly connecting bars 8 and 9 and also the bearing sections 12 and 13. These bearing sections are secured to the side bars 8 and 9 by riveting or in any other suitable manner and are provided at their upper ends with registering semicircular grooves 17 which form when these sections are brought together, a bore 18 to receive one of the pintles 19 of the churn or other vessel C to be suspended within the frame.

It is to be understood that these A-shaped end members are constructed exactly alike and hence one only has been described in detail.

The end members 1 and 2 of each frame are connected by diagonally disposed braces 20 and 21 which are preferably composed of angle iron, each having a laterally extending flange along one side edge thereof as is shown clearly at 22 in Fig. 2. Each of these braces is pivotally connected at its opposite ends with one of the side bars of each end member 1 and 2 and one of said braces has its ends disposed on the outer face of said bars while the other is disposed on their inner faces as is shown clearly in Fig. 2 with the flanges 22 of said braces, one extending outwardly and the other inwardly so that the flat, smooth faces of these braces will be dis-

posed adjacent each other and avoid unnecessary spacing thereof. As shown in Fig. 2, brace 20 is pivotally connected at its lower end with the inner face of the side bar 9 of the end member 1 and at its upper end is pivotally connected with the inner face of the side bar 9 of the other end member 2 while brace 21 is pivotally connected at its lower end with the outer face of the side bar 9 of member 2 and at its upper end with the outer face of the side bar 9 of member 1, said upper brace ends being arranged adjacent the upper ends of said side bars so that when the frame is in expanded operative position it will be firmly braced throughout its height.

Each of these braces 20 and 21 is composed of two pivotally connected sections as 23 and 24, the connected ends of which are 20 arranged in overlapping relation in the same manner that the section ends of the cross bars 3 are connected, the flange 22 at the inner end of one section being cut away and that of the adjacent end overlapping 25 the cut away portion so that when the brace sections are in longitudinal alignment, this overlapping flange will operate to hold the braces against further downward movement.

It will thus be seen that when the braces 30 20 and 21 are in open operative position as shown in Fig. 2, and the side bars 8 and 9 have been expanded and held in open position by the cross bars 3 as shown in full lines in Fig. 1, the frame is in position for 35 supporting the churn barrel C or any other vessel to be supported thereby. In order that this churn may be mounted in said frame, the bearing sections 12 and 13 are separated to receive the pintles 19 of the 40 churn by first breaking the joints of the cross bars 3 and moving the side bars 8 and 9 of the two A-shaped members toward each other a sufficient distance to cause the bearings to open at their upper ends as shown in 45 dotted lines in Fig. 1 and when in this position the pintles may be lowered into said bearings and the end members opened up into the position shown in full lines in Fig. 1 whereby the bearing sections 12 and 13 are 50 closed around said pintles and afford a firm support for the churn.

After these members have been so positioned they are locked against collapse by means of a cross bar 25 which is pivotally 55 connected at one end with the lower end of one of the side bars of the A-shaped member 2 and has detachable engagement at its other end with the corresponding side bar of the A-shaped member 1 as is shown 60 clearly in Fig. 2. In this figure the cross bar 25 has its free end inturned to form a hook 26 which is engaged with a slot 27 formed in said bar 9 of member 1 and when this bar 25 is so positioned, the frame is held 65 against collapse and can only be folded after

said bar has been disengaged from said bar 9.

When it is desired to collapse this frame, the bar 25 has its hook 26 disengaged from slot 27 and the bar is swung upwardly and disposed parallel with bar 9 of end section 2. The joints in the cross bars 3 of the end members are then broken and the lower ends of the side bars of said members moved toward each other thereby causing their upper ends to separate and open the bearings carried thereby so that the churn C may be lifted from said frame and deposited at any suitable point. The further collapse of the frame is accomplished by bringing the lower 75 ends of said bars 8 and 9 of the two sections into contact with each other and then breaking the joints in the sections of the braces 20 and 21 and folding said braces upwardly as shown in dotted lines in Fig. 2, the folding being continued until said braces are in completely folded position and when in this position, the braces 20 will be housed within the bars of the end members while the braces 21 will be disposed on the outer face of said 80 bars and lie in close proximity thereto. It will thus be seen that the frame when so collapsed will occupy a very small space and may be conveniently stored or shipped.

From the foregoing description, taken in connection with the accompanying drawings, the advantages of the construction and of the method of operation will be readily apparent to those skilled in the art to which the invention appertains and while I have 100 described the principle of operation of the invention together with the device which I now consider to be the best embodiment thereof, I desire to have it understood that the device shown is merely illustrative and 105 that such changes may be made as are within the scope of the claimed invention.

I claim:—

1. A collapsible frame including foldable end members, foldable brace bars connecting 110 said members, and a cross bar pivotally connected at one end with one end member and detachably engaged at its other end with the other end member whereby the frame is held against collapse.

2. A collapsible frame including A-shaped end members, each composed of pivotally connected side bars with a cross bar connecting them and composed of sections, pivoted to fold in one direction, means for locking 120 said sections against pivoting in the opposite direction, folding braces connecting said end members, and means for locking said braces in open position.

3. A collapsible frame including A-shaped 125 end members, each composed of pivotally connected side bars with a cross bar connecting them and composed of sections pivoted to fold upwardly, coöoperating means on said sections for locking them in longi- 130

tudinal alinement against downward folding, upwardly folding braces connecting said end members, means for locking said braces against downward folding, and a 5 cross bar detachably connecting said end members to hold the frame in operative position.

4. In a frame of the class described, a pair of A-shaped end members, the side bars 10 of which are pivotally connected at their meeting ends and the cross bars composed of pivotally connected sections and pivotally

connected with said side bars near their lower diverging ends, said cross bars being foldable inwardly and held against outward 15 folding, foldable braces connecting said end members, and means for locking said braces against folding.

In testimony whereof I affix my signature in presence of two witnesses.

FRED MARTINSON.
